SPUT CONNECTION FOR FLEXIBLE PLATE

Michael J. Quillinan, Bronx, N. Y.

Application May 5, 1952, Serial No. 286,097

5 Claims. (Cl. 285—38)

The present invention relates to closure construction generally, and particularly to closures useable on any type of non-rigid container wall and to contain any specified fluid.

In the art of closure fabrication and insertion, it is oftentimes difficult to provide a closure of universal use. Sealing integrity is a particularly difficult problem for one must consider; (a) the relative position of the threads and the sealing means, (b) the stress and strain on material of the container wall and the closure elements during closure insertion and use, (c) the necessity for continued maintenance of sealing integrity required during shipment of the container and its closure.

I have provided a practical solution to the problem of sealing integrity for closures for non-rigid container walls.

My invention comprises an annular closure fitting and container wall combination; the fitting includes a first collar having a flange projecting inwardly from its lower edge; an outer collar complementary to the first collar has a flange projecting outwardly from the lower edge of the outer collar. The flanges of the collars rest on the container wall. An annular rigid member is affixed to the container wall beneath the plane thereof for supporting each of said collars and flanges. The inner edge of the annular rigid member overlies the inwardly projecting flange, and the upper free edge of the first collar overlies the upper free edge of the outer collar. Sealing portions are provided on the container wall in the area of joinder of the collars and flanges.

The figure is a perspective view of the closure with parts broken away and in section.

Referring to the figure a preferred modification of the closure is shown. A fitting is provided at 10, generally, and comprises an annular inner and outer collar 11 and 12 having threads rolled therein and respective inwardly and outwardly directed flanges 13 and 14 at the lower extremities thereof. The inner collar 11 is preferably provided with a curled annulus 15 impeding the upper free end of collar 12 and adapted to receive a cylindrical wall 16 of a capseal generally shown at 17.

Container wall 39 is compressed in sealing relation between the underfaces of flanges 13 and 14, and the upper face of a perforate disc-like supporting member 40 which evenly engages the container wall adjacent its opening. The inner extremity of supporting member 40 is curled over the lip of flange 13 and wall 39 as at 41 to compress the container wall. To insure against rotation of the fitting 10 relative to the container wall, the outer edge of flange 14 is cupped polygonally downward as at 21a, and the outer edge of supporting member 40 is trimmed polygonally and complementary to portion 21a of flange 14. The container wall is assured of a more permanent sealing relation of parts by reason of the rigid supporting member 40 being non-rotatable with respect to fitting 10. The container wall 39 is further stationed relative to fitting 10 by means of a ring 44 integral within wall 39, the ring being located coaxially in the mouth of the fitting at the

2

point of joinder of the flanges 13 and 14 and the collars 11 and 12.

A plug 24 with a threaded wall 25 and flat bottom 26 is adapted to be screwed into the fitting 10 by wrench-engaging lugs 27 provided around wall 25 on bottom 26. The under face of plug 24 is adapted to seat gasket 26a between the recess provided between an over-hanging portion of wall 25 generally shown at 27 and the periphery of bottom 26. The plug 24, when threaded into place, 5 axially depresses gasket 26a onto portions of the lip of flange 13 and the curled free end 41 of supporting member 40, thereby sealing the joint therebetween.

Capseal 17 is seated on the top of plug 24 through a gasket 28 resting upon the top 29 of wall 25 and the lower part of annulus 15 and is compressed thereagainst by the tucking of capseal wall 16 within annulus 15.

The annulus 15 is interrupted, as disclosed in my co-pending application for a capseal S. N. 171,697, at least one point in its circumference to define a gap, through the sides 30 of which pass one tearing ear 31 extending from the plane of the periphery of capseal bottom portion 32 which in turn bears upon gasket 28. Wall 16 of capseal 17 is correspondingly interrupted about its circumference such that a tearing strip generally shown as 33 may be defined across bottom portion 32 by scored lines of weakness 34 induced therein and terminating at the lateral sides of ear 31 and the foot wall 16.

Clear height of a closure from the wall 10 is not sacrificed in the fitting since the threads are placed at the lowermost part of collar 11. This is most effectively accomplished by thread rolling techniques old in the art, it being impractical to attempt to cut threads internally at the close space between flange 13 and collar 11. Thread rolling dually affords for the provision of annulus 15 which has two functions, i. e., (a) the co-operation with polygonally shaped flange 14 to prevent rotation and upward displacement of collar 11 with respect to collar 12, and (b) to provide a seat for capseal wall 16.

Although collar 12 is also shown as of rolled fabrication, it may be economically threaded by cutting techniques also old in the art of internal threading.

In assembly collars 11 and 12 may be rolled together from a cylindrical wall or they may be screwed together 45 at the point of insertion of the fitting.

By adopting thread rolling techniques, it is possible to simultaneously roll annulus 15 into the collar 11. This serves two purposes, viz., the provision of a seat for the wall 16 of capseal 17 and the providing of means to 50 obstruct the collar 12 from upward axial displacement, whether that latter collar be threaded or not.

By making the collars 11 and 12 separately it was possible to fabricate the fitting 10 at the point where the fitting is to be inserted on the container wall.

55 Providing flange 13 at the foot of collar 11 enables the placing of a gasket 26a between the container's contents and the plug 24 enabling the use of a noncorrosion resistant plug 24 and threaded wall 25.

I claim:

1. An annular closure fitting and container wall in combination, said fitting including a first collar having a flange projecting inwardly from its lower edge, an outer collar complementary to said first collar and having a flange projecting outwardly from the lower edge of said outer collar, the flanges of said collars resting on said container wall, an annular rigid member affixed to said container wall beneath the plane thereof for supporting each of said collars and flanges, the inner edge of said annular rigid member overlying said inwardly projecting flange, the upper free edge of said first collar overlying the upper free edge of said outer collar, and sealing por-

tions on said container wall provided in the area of joinder of said collars and flanges.

2. A closure fitting and container wall in combination according to claim 1, in which said first collar has threads provided therein commencing substantially in the plane of said inwardly projecting flange and progressing axially upward, said threads being characterized in section as a zig-zag progression along said first collar.

3. An annular closure fitting and container wall in combination, said fitting including a first collar having a flange projecting inwardly from its lower edge, an outer collar complementary to said first collar and having a flange projecting outwardly from the lower edge of said outer collar, said container wall being composed of a rubber-like material, the flanges of said collars resting on said container wall, an annular rigid member abutting an opposite side of said container wall from that side on which said flanges rest, the upper free edge of said first collar overlying the upper free edge of said outer collar, the inner edge of said annular rigid member overlying said inwardly projecting flange in the form of an annular curl with an annular free edge of said container wall lying therebetween.

4. A closure fitting and container wall in combination according to claim 3, in which said first collar has threads provided therein commencing substantially in the plane of said inwardly projecting flange and progressing axially upward, said threads being characterized in section as a zig-zag progression along said first collar.

5. A closure fitting and container wall in combination according to claim 3, in which a ring is imbedded in the container wall and occupies the area of joinder between said collars and said flanges.
